US0D1027203S

(12) **United States Design Patent** (10) **Patent No.:** **US D1,027,203 S**
(45) **Date of Patent:** **** May 14, 2024**

(54) **BEAUTY APPARATUS**

(71) Applicant: **Shenzhen Ulike Smart Electronics Co., Ltd**, Shenzhen (CN)

(72) Inventor: **Yuping Pan**, Shenzhen (CN)

(73) Assignee: **Shenzhen Ulike Smart Electronics Co., Ltd**, Shenzhen (CN)

(**) Term: **15 Years**

(21) Appl. No.: **29/881,347**

(22) Filed: **Dec. 30, 2022**

(30) **Foreign Application Priority Data**

Aug. 16, 2022 (CN) 202230535111.8

(51) **LOC (14) Cl.** **24-01**

(52) **U.S. Cl.**

USPC **D24/209**

(58) **Field of Classification Search**
